Re. 15,511

UNITED STATES PATENT OFFICE.

HENRY ST. PIERRE, OF WORCESTER, MASSACHUSETTS.

ANTISKID DEVICE.

Original No. 1,363,994, dated December 28, 1920, Serial No. 325,983, filed September 24, 1919. Application for reissue filed July 28, 1921. Serial No. 488,173.

To all whom it may concern:

Be it known that I, HENRY ST. PIERRE, a citizen of the United States, residing at Worcester, in the county of Worcester and 5 State of Massachusetts, have invented a new and useful Antiskid Device, of which the following is a specification.

This invention relates to an anti-skid device for automobile tires, and has for its 10 primary object to provide a device in which the tread members are so associated that movement of the device on the tires will be absolutely prevented, and besides increase the gripping action between the device and 15 the ground, created upon the tendency of the tires to skid.

An object of the invention is to provide 20 means for quickly clamping the device in place upon the tires, and capable of taking up all slack in the device when in an applied position.

With these and other objects in view the invention will be better understood from the following detailed description taken in connection with the accompanying drawings, 25 wherein:

Fig. 1 is a side elevation of an automobile wheel with my invention applied thereto;

30 Fig. 2 is a similar view with two of the tread members in the position they assume when the tire tends to skid;

Fig. 3 is a cross section view through the tire;

35 Fig. 4 is an edge view of a portion of the device;

Fig. 5 is a cross section view of one of the members;

Fig. 6 is an enlarged side elevation of the 40 clamp;

Fig. 7 is a cross section view thereof; and

Fig. 8 is a perspective view of the clip.

Again referring to the drawings illustrating the preferred one of the many forms in 45 which the invention may be constructed a numeral 1 designates a plurality of tread members arcuate shape so as to conform to the tread of the tire. The intermediate portion of each member is provided with radially extending flanges 2 for engagement with the ground. Links 3 flexibly connect openings 4 in the members with chains 5. By this arrangement as clearly shown in Fig. 2 of the drawings, the gripping effect 55 between the members and the ground will

be materially increased when the tire tends to skid, owing to the fact that the frictional engagement of the flanges with the ground will force the members in a direction to bring a greater portion of each member into engagement with the ground. It will also be noted that a portion of each chain 5 is forced out of its normal position which materially increases the pressure between the upper members and the tire thereby absolutely preventing slipping of the device on the tire.

A feature of my invention is the clamp 6 which enables me to quickly arrange the device in place and take up any slackness 70 in the chain. This clamp consists of a ratchet element 7 pivotally connected to one end of the chain and the clip 8 pivotally connected to the other end of the chain. The clip 8 is provided with a guide way 9 75 for the reception of the element 7 and a slot 10 arranged so as to allow the free end 11 of the spring 12 to enter the slot 10 and engage anyone of the teeth of the ratchet element. The spring has an intermediate 80 portion 13 pivoted to a rivet 14 in the clip while its remaining end 15 is arranged in recess 16 in the clip, so that the clip may have the proper degree of resiliency in its engagement with the teeth.

It is of course to be understood that the invention may be constructed in various other manners and the parts associated in other relations, and therefore I do not desire to be limited in any manner except as 90 set forth in the claims hereunto appended.

What I claim is:

1. A chain fastener comprising a loop-like guide member carried by one end of a chain, a ratchet member carried by the other end of the chain and slidable through said guide and formed with a plurality of notches, a U-shaped spring secured upon said guide and having its bight portion engageable within a selected one of said 100 notches and said guide having a slot for the reception of the bight portion of the spring.

2. A chain fastener comprising a loop-like guide member carried by one end of a chain, a ratchet member carried by the other end of the chain and slidable through said guide and formed with a plurality of notches, a spring connected with said guide, located outside it, and having a cross piece engageable within a selected one of said 110

notches and said guide having a slot into which the bight portion of the spring extends from the outside.

3. A device of the class described comprising a member having a slotted housing at one end thereof, a bar working in said slot, a spring for operating said bar placed outside of the housing for holding the bar in the inner part of the slot, the external 10 sides of the housing acting as guides for said spring, and a rack bar adapted to be passed through said housing and to receive the cross bar between its teeth.
4. In combination with an anti-skid device, a member engaging one of the end links of the device, a housing on said member having a slot through its wall, a rack member connected with the other end link and adapted to be passed into the housing, 20 a cross bar working in the slot in the hous-

ing and engaging the teeth of the rack member, and a spring pressed member mounted on the outside of the housing carrying said cross bar.

5. A tire chain fastener comprising a 25 toothed rack pivotally attached to one end of a chain, a casing pivotally attached at one side to the other end of the chain, said casing having its ends open, whereby the rack can be adjusted to a position in which 30 its end projects beyond the casing, a pawl movable within said casing, and means for yieldingly forcing the pawl into engagement with the toothed rack upon insertion of the said rack into the casing, for permitting the 35 adjustment of the chain upon the vehicle wheel.

In testimony whereof I have hereunto affixed my signature.

HENRY ST. PIERRE.
